UNITED STATES PATENT OFFICE

WILLIAM L. LENTZ, OF TUCKAHOE, NEW YORK, AND HARRY M. PFLAGER, OF ST. LOUIS, MISSOURI, ASSIGNEES TO GENERAL STEEL CASTINGS CORPORATION, OF GRANITE CITY, ILLINOIS, A CORPORATION OF DELAWARE

LOCOMOTIVE STRUCTURE

Application filed December 3, 1931. Serial No. 578,650.

This invention relates to railway rolling stock and consists particularly in a novel construction of locomotive underframes including various internal passages arranged to 5 serve as steam and water conduits.

On previous locomotives the steam pipes extending from the cylinder saddle to the booster engine and exhaust steam injector, and the water pipe leading from the tender 10 to the water pump have been mounted on the outside of the locomotive underframe or superstructure. The space required for mounting these pipes on the outside of the underframe or locomotive structure, especially the 15 space for the large exhaust steam pipe extending from the main exhaust steam passages in the cylinder saddle to the exhaust steam injector, is very limited and considerable difficulty has been experienced in mounting these 20 pipes so as not to interfere with other parts of the locomotive, and so as not to greatly affect the general appearance of the locomotive.

The main object of the present invention is 25 to eliminate the above difficulties and improve the general appearance of the locomotive by constructing an underframe having various internal passages through which steam may be conducted from the cylinder saddle to the 30 injector and booster motor and water from the rear of the frame to the feed water heater mounted at the front.

Another object is to further improve the appearance of the locomotive and provide additional space for mounting other equipment 35 by constructing the main air reservoir integral with the locomotive bed and between the side frames instead of securing the reservoir on the outside of the bed or locomotive superstructure, as is frequently done at present.

These general objects and other more detailed objects are attained in the structures illustrated in the accompanying drawings in which—

45 Figure 1 is a top view of the front half of an integral locomotive underframe structure embodying one form of the invention.

Figure 2 is a side view of the same.

50 Figure 3 is a top view of the rear half of the underframe.

Figure 4 is a side view of the same showing a portion of the firebox, boiler, trailing truck, and other equipment.

Figure 5 is a vertical transverse section taken on the line 5—5 of Figure 4. 55

Figures 6, 7, 8, and 9 are detail vertical transverse sections taken on the corresponding section lines of Figure 4.

Figures 18 to 25 are vertical half sections taken on the corresponding section lines of Figure 16. 65

Figure 26 is a vertical transverse section taken on the line 26—26 of Figure 15. 70

Figure 27 is a top view of a portion of a locomotive bed embodying another modified form of the invention.

Figure 28 is a side view of the same.

Figures 29 and 30 are vertical transverse half sections taken on the corresponding section lines of Figure 27. 75

Figures 31 and 32 are vertical transverse half sections taken on the corresponding section lines of Figure 28. 80

In Figures 1 to 14, the various conduits are formed integrally with the one-piece underframe shown which includes box section side members 2 and pedestals 3 braced by suitable transverse ribs 2a and an elongated box section main body structure 6 extending longitudinally between the side members. Pedestals 3 are formed integral with the side members, and the side elements of cradle 4, which support firebox 48, ash pan 43, and hopper 44, comprise extensions of the side members and the main body member. A bracket 5 projects from the right hand element of the cradle 4 (Figure 5) for mounting an injector 23. The rear portion of the underframe includes buffering plate 7, rear deck structure 8, and laterally projecting arms 9 for engaging rocker bearings 10 carried by the trailing truck 11. The forward portion of the casting includes front deck 100

1 and the usual cylinder saddle comprising main steam cylinders 12, valve chambers 13, and boiler saddle 14.

5 Valve gear brackets 15, guide yoke brackets 16, brake hanger brackets 17, equalizer fulcrums 18, spring hanger lugs 18a, brake lever fulcrums 19, and expansion plate brackets 20 are all of known design and in themselves do not constitute the present invention. 10 Mounted on each side of the forward deck 1 are a feed water pump 21 and an air compressor 22. An exhaust steam injector 23 is secured to bracket 5 and a booster motor 24 is mounted on the trailing truck 11 beneath the rear end of the underframe and cab 25.

15 Exhaust steam is supplied to the injector 23 from main exhaust passage 26 in the cylinder saddle 14 through a pipe 27 and oil separator 28. Pipe 27 connects with a conduit 29 which is supported near its forward end by an upright transverse rib 30 and merges with passage 31 extending the length of the underframe casting beneath the elevated top 25 web 6a of the box-shaped body portion 6 of the casting. Passage 31 extends through the inclined portion of the top web near the rear end of the main frame and connects with pipe 32 leading to the injector. Feed water, 30 entering the injector through suction pipe 33, is delivered to the boiler through pipe 34 which contains a check valve.

35 Live steam is fed to the booster motor 24 through a pipe 35 and throttle valve 36 which are connected with conduit 37 and passage 38, corresponding with the conduit 29 and passage 31, respectively, on the other side of the underframe. A pipe 39, secured to fire box 48 by brackets 40, conducts steam from 40 passage 38 to the booster motor. The booster exhaust passes through pipe 41 to a passage 42 which extends through the hollow right hand cradle element (Figure 5) and then through the elongated body member 6 paralleling injector passage 31. Passage 42 merges in the cylinder saddle with main exhaust passage 26 from the valve chests 13. Upright ribs 49 traverse the box-shaped backbone member of the underframe at intervals 45 and serve to brace the underframe and support pipes 31 and 38.

50 Another feed water supply from the tender is directed through pipe 45 connecting with passage 46 formed in the underframe and corresponding with booster exhaust passage 42. A pipe 47 connects passage 46 with the feed water pump 21.

55 The different passages will necessarily vary somewhat in size and shape according to the contour of the underframe at different points along its length, but the casting is preferably made substantially uniform on each side of the longitudinal center line thereof in order to maintain proper balance and appearance and conform with strength

requirements. The passages 42 and 46 occupy hollow portions of the underframe, and the passages 31 and 38 are located in the interior of the box section body member 6, which space is ordinarily not utilized. Thus, 70 difficulties experienced in mounting the various conduits on the outside of the frame are eliminated and additional space is provided which facilitates the mounting of other equipment. 75

In Figures 15 to 26 is illustrated a locomotive underframe including box-section backbone member 53 traversed at intervals by internal upright ribs 54 having substantial cored openings 86. Member 53 is open at 80 both ends and the side walls thereof diverge at each end as at 87 and 89 and merge with underframe side members 55.

85 Fluid pipes 50 and 51 extend longitudinally through the inside of member 53, passing through cored openings 86 in ribs 54, and are supported from the top web of member 53 by hangers 57, clearly shown in Figures 22 and 25. The complete pipe supporting brackets are inserted through convenient openings in 90 the structure and applied to the pipes at suitable points by means of curved straps 58 and 59 and bolts 60. With the boiler and firebox, a portion of the latter being shown at 61, in position on the underframe, the horizontal portions of pipes 50 and 51 can be applied to or removed from the underframe through openings 56 in the front and rear walls of the boiler saddle 63. The top central portion of the deck plate 64, supported by diagonal ribs 84 and 85, is depressed below the level of pipes 50 and 51 so as not to interfere with insertion or removal of the 95 pipes. 100

105 Pipes 50 and 51 each may comprise two or more sections within member 53 which are secured together by means of bolting flanges or, if desired, they may each consist of a single pipe within member 53. Pipe 51 connects with the adjacent steam chest 65 through booster throttle valve 66, and, at the rear end of member 53, connects with a pipe section 67 leading around the fire-box to the booster motor. This pipe may also be used 110 to conduct water from the tender to the feed-water pump 62, as indicated in broken lines in Figure 15, if desired. Pipe 50 connects at the front end with oil separator 68 and a main exhaust passage 70 in the cylinder saddle, and at the rear end with pipe 69. Exhaust steam is diverted rearwardly through 115 pipes 50 and 69 to the exhaust steam injector (not shown) which is preferably mounted on a bracket projecting from the side of the 120 cradle 71.

125 It will be seen that in this form the walls of member 53 are insulated from the portions of the pipes 50 and 51, located within member 53, by intervening air space and that only 130

a negligible amount of heat will be transmitted through hangers 57. Pipes 50 and 51 may, if desired, serve for other purposes, pipe 51 being readily utilizable as a passage 5 for feed water from the tender to the feed-water pump, and pipe 50 being conveniently located for conducting exhaust steam from the booster to the cylinder saddle. No passages are provided corresponding with integral 10 passages 42 and 46 in the first form.

In Figures 27 to 32, conduits 72 and 84 pass through perforations 82 in a sloping web 73 which extends across the rear end of hollow backbone member 74, and through cored 15 openings 75 in ribs 76 in the interior of the member. The portions of the conduits 72 and 84 which are located within member 74 are spaced from the walls of the member, as in the form previously described, and are supported from the curved top web of the member by brackets 78. A main air reservoir 77 is formed integral with a depressed portion of the top web of the backbone member 74. Cleaning openings 79 in the reservoir 20 are closed after casting by steel plates welded in place. The reservoir is further braced by diagonal ribs 90.

Reservoir 77 intersects the rear boiler expansion plate bracket 80 and the corresponding boiler expansion plate P must be divided, in order to clear the reservoir, and secured to portions of the bracket on each side of the upwardly projecting reservoir structure. Expansion plate bracket 81 and other similar brackets, beyond the front end of the reservoir, may extend entirely across the bed in the usual manner. Brake hanger brackets 83 are provided at the outer ends of expansion plate brackets 80 and 81.

Obviously the structure illustrated might be otherwise varied as to details. Other pipes could be located within the hollow backbone member of the underframe in Figures 15 to 25 and other methods of mounting the pipes might be adopted in Figures 15 to 32. The particular general form of the bed and its parts is not essential. Also the various passages and conduits could be used for other purposes than those described. These and other modifications might be made without departing from the spirit of the invention and the exclusive use of all such variations as come within the scope of the appended claims is contemplated.

We claim:

1. A cradle for a locomotive underframe including spaced side elements, one of said elements being hollow and serving as a fluid conduit.
2. A cradle for a locomotive underframe including a side member having a wall, said wall forming at least a portion of the wall of a fluid conduit.
3. In a locomotive underframe, a main frame portion, and a cradle having a hollow

side member serving as part of a fluid conduit, said conduit also extending through said frame portion.

4. In a locomotive underframe, a main frame, a cradle comprising an extension on 70 said main frame and having a hollow side member, and a fluid conduit formed in part by said hollow side member and extending through said underframe.

5. In a locomotive underframe, a main frame with pedestals, a cradle comprising an extension on said main frame and having a hollow side member, and a fluid conduit formed in part by said hollow side member and extending through said underframe 75 alongside of said pedestals.

6. In a locomotive underframe integral structure, a forward steam cylinder portion, a rear cradle portion, a main body member, and a fluid conduit extending between said portions, a substantial part of said conduit being located within said body member and extending substantially from end to end thereof.

7. In a locomotive, an underframe including a cradle having a side member, driving wheels, and a fluid conduit extending longitudinally through the portion of said underframe abreast said driving wheels and through said side member.

8. In a railway vehicle underframe integral structure, spaced side members, an elongated hollow member bracing said side members, and a pair of fluid conduits extending longitudinally through the interior of said 100 bracing member and projecting out through the top web thereof.

9. In a railway vehicle underframe integral structure, spaced side members, an elongated hollow brace therefor, and a plurality of fluid conduits, one of said conduits extending through said brace and being spaced therefrom except at its point of passage through the wall thereof, and another of said conduits being formed by a partition in said 105 brace.

10. In a locomotive underframe integral structure, spaced side frames, a transverse brace, a cradle including a side element, and a fluid conduit extending longitudinally of 115 said underframe through said side element and said brace.

11. In a locomotive underframe integral structure, spaced side frames, a cradle including a side element, an elongated hollow body member extending longitudinally between said side frames, and a fluid conduit extending longitudinally of said underframe through said side element and said body member.

12. In a locomotive underframe integral structure, spaced side frames, an elongated reinforcing structure extending longitudinally between said side frames, an upright rib extending transversely across the top of 130

said member, and a fluid conduit extending longitudinally within said member and having a portion passing through the top thereof and supported by said rib.

13. In combination, a side frame member for a railway vehicle underframe, and a steam passage adjacent said member, said member being hollow throughout at least a portion of its length and comprising a conduit for conducting steam to or away from said passage.

14. In combination, a locomotive underframe member, and a feed-water pump positioned near said member, said member being hollow throughout a substantial portion of its length and comprising a conduit for conducting feedwater to or away from said pump.

15. In combination in a locomotive, an underframe including an elongated main body member, a steam passage near one end of said underframe, a booster motor steam pipe located adjacent the other end of said underframe, and a steam conduit connecting said passage and said pipe, a substantial portion of said conduit being located within and spaced from the walls of said body member.

16. In combination in a locomotive, an underframe including an elongated main body member, passages for live steam and exhaust steam near one end of said underframe, booster motor steam supply and exhaust pipes near the other end of said underframe, and conduits connecting said passages with said pipes, substantial portions of said conduits being positioned within said body member and spaced throughout their lengths therefrom.

17. In combination, a locomotive underframe including spaced side frames having pedestals, an elongated hollow member bracing said side frames, a steam passage, and an auxiliary conduit leading from said passage rearwardly through the interior of said bracing member and alongside of said pedestals, a portion of said conduit being integral with said member.

18. In combination, a locomotive underframe including spaced side members and a member bracing said side members, a booster motor located adjacent one end of said underframe, a steam passage located near the opposite end of said underframe, and a conduit connecting said booster motor and said passage and leading through a portion of one of said side members and through said bracing member, portions of said conduit being integral with said bracing and side members.

19. In combination in a locomotive, an underframe including an elongated main body member, a water supply pipe near one end of said underframe, a feedwater pump adjacent the other end of said underframe, and a conduit connecting said pipe and said

pump, a substantial portion of said conduit being within said body member and spaced from the walls thereof.

20. In combination in a locomotive, an underframe including an elongated main body member, an exhaust steam passage adjacent one end of said underframe, an injector exhaust steam pipe spaced longitudinally of said underframe from said passage, and a conduit connecting said passage and said supply pipe, a substantial portion of said conduit being within said body member and spaced from the walls thereof.

21. In a steam locomotive, an underframe having spaced side members including pedestals and a bracing member extending longitudinally between said side members, and a separate fluid conduit extending along said side members and pedestals and through said bracing member, said conduit being spaced from the walls of said member so as to provide for expansion of said conduit without causing excessive stresses in said underframe.

22. In a locomotive underframe, a longitudinal body member including pedestals and a fluid conduit extending substantially throughout the length of said body member and alongside of said pedestals and secured to a wall of said member by brackets, said brackets maintaining said conduit spaced from the walls of said body member.

23. In a locomotive underframe, a longitudinal body member including pedestals, a bracing rib extending transversely of the interior of said body member and having a perforation therein, and a fluid conduit extending through said body member and said rib and alongside of said pedestals and spaced from said rib and the walls of said member.

24. In a locomotive underframe, a longitudinal body member including pedestals, and a fluid conduit extending through said body member and alongside of said pedestals and secured to said member by brackets, each of said brackets comprising an element projecting from a wall of said body member and a pair of straps secured to said element and shaped to grip said conduit between them.

25. In a locomotive underframe, a longitudinal body member including pedestals and a fluid conduit extending through said body member and alongside of said pedestals and secured to said body member by brackets, each of said brackets comprising an element projecting from a wall of said body member and a pair of straps secured to said element and shaped to grip said conduit between them, and said brackets maintaining said conduit spaced from the walls of said body member.

26. In a locomotive underframe, a hollow longitudinal body member and an air reservoir integral with and having its lower portion formed by the top wall of said body member.

27. In a locomotive underframe, spaced side members, an elongated bracing member extending therebetween, and an air reservoir integral with and located wholly above the 5 level of said bracing member.

28. In a locomotive underframe, a main longitudinal hollow body member including a top web having a depressed portion, and an air reservoir projecting upwardly from 10 said top web, said depressed portion forming a part of said reservoir.

29. In a locomotive underframe, a main longitudinal hollow body member, an air reservoir projecting above said body member, and a boiler expansion plate bracket on each 15 side of said reservoir.

30. In a locomotive underframe, an elongated body member and an air reservoir located above said body member, and a fluid 20 conduit extending through said body member and spaced from the walls thereof and from said reservoir.

31. In a locomotive, an underframe having 25 side members, a longitudinal bracing member between said side members, and an air reservoir located above said bracing member and integral therewith, and a fluid conduit extending through said bracing member and spaced from the walls thereof and from said 30 reservoir.

32. In a locomotive, an integral underframe structure including an elongated hollow body member and an air reservoir, the 35 top wall of said body member including upwardly inclined side portions and a depressed intermediate portion, and said depressed portion forming a portion of the wall of said reservoir, brackets depending from the upwardly inclined portions of said top wall, and a fluid conduit mounted in said brackets 40 and spaced thereby from the walls of said body member and said reservoir.

33. In a locomotive, an underframe including 45 a boiler support having a transverse upright member and a longitudinal framing member extending rearwardly from said support, said upright member having an opening therein, and a fluid conduit extending 50 through said framing member and spaced from walls thereof, said opening being adapted to permit the application or removal of said conduit through the front of said support.

34. In a locomotive, an underframe including 55 a boiler support having a transverse upright member, a longitudinal framing member extending rearwardly of said support, and a deck plate extending forwardly of said support, said upright member having an opening therein, and a fluid conduit extending 60 through said framing member and spaced from the walls thereof, the top of the center portion of said deck plate being disposed below 65 the level of the bottom of said conduit so

as to permit the application or removal of said conduit through said opening.

35. In a locomotive, an underframe including a boiler support, a longitudinal framing member extending rearwardly of said support, a deck extending forwardly of said support, and a fluid conduit extending through said framing member, said support and deck being shaped to permit the application of said conduit to said underframe 70 from the front end thereof. 75

36. In a locomotive, an underframe including a boiler support and a longitudinal framing member extending rearwardly of said support, and a fluid conduit extending through said framing member, said support being shaped to permit the application of said conduit to said underframe from the front 80 end thereof.

37. A railway locomotive integral underframe structure including an elongated hollow backbone member and a fluid conduit extending through said member, said conduit being spaced from said member except at 85 spaced points of support. 90

In testimony whereof we hereunto affix our signatures this 21st day of November, 1931 and 17th day of November, 1931, respectively.
